UNITED STATES PATENT OFFICE.

CHARLES S. SPITZER AND JOHN GLOUB, OF CHICAGO, ILLINOIS.

CABINET FOR PHONOGRAHS.

1,402,383.

Specification of Letters Patent.

Patented Jan. 3, 1922.

Application filed May 4, 1921. Serial No. 466,836.

To all whom it may concern:

Be it known that we, CHARLES S. SPITZER and JOHN GLOUB, both citizens of the United States, and residents of Chicago, in the county of Cook and State of Illinois, have invented certain new and useful Improvements in Cabinets for Phonographs, of which the following is a full, clear, and exact description.

10 The invention relates to cabinets for phonographs. One of its objects is to provide improved mechanism for holding record-disks so they can be conveniently manipulated into and out of the case. Another 15 object of the invention is to provide means for exhibiting a placard in connection with the withdrawal of a record from the cabinet, so that the matter on the placard will be displaced while the record is being reproduced 20 by the phonograph.

The invention consists in the several novel features hereinafter set forth and more particularly defined by claims at the conclusion hereof.

25 In the drawings: Fig. 1 is a vertical longitudinal section of a phonograph-cabinet embodying the invention. Fig. 2 is a section taken on line 2—2 of Fig. 1. Fig. 3 is a detail of one of the slidable record-holders. 30 Fig. 4 is a horizontal section taken on line 4—4 of Fig. 1. Fig. 5 is a detail section through the arms operated by the record-holding slides to operate the exhibiting devices. Fig. 6 is a section taken on line 6—6 35 of Fig. 1.

The invention is exemplified in a cabinet 8 which is provided with a top 9, on the underside of which a case 10, containing a motor (not shown) for driving a rotatable 40 record-table 11, is supported. A cover 12 contains an amplifier which is connected to a reproducer 13 in any suitable manner or as set forth in an application filed by us May 7, 1921, Serial No. 467,755.

45 Cross bars 14 are rigidly secured in the lower portion of the cabinet and a series of longitudinally extending channeled bars 15 are secured on said cross-bars. A slide 16 is fitted in each of the channeled bars 15 50 and has secured thereto a pair of plates 17 which are adapted to hold between them a record-disk 18. The plates 17 are cut away, as at 19, so that a portion of the record-disk will be accessible to be gripped in removing 55 or replacing it in the holder. The front end of each slide 16 is provided with a handle 20

whereby the slide may be shifted into and out of the cabinet. The lower portion of the cabinet is provided with hinged doors 21 to provide access to that portion of the chamber in the cabinet which contains the record-holders, it being understood that the slides 16 are movable longitudinally, so that the record disks and their holders may be withdrawn from the cabinet, as shown by dotted lines in Fig. 1.

The invention contemplates exhibiting a placard containing the words of a song or an advertisement or a picture or any other matter which it might be desirable to exhibit while the records are being reproduced. For this purpose, a series of rectangular frames 22 normally rest on a horizontal bracket 23, which is fixed in the case. Each of these frames is provided with four upwardly extending holders each adapted to contain a transparent placard 25, there being one placard for each of the four sides of the cabinet. That portion of the cabinet which is above the holders, while they are in their lowered or normal positions, is provided with windows 26, through which the placards will be visible when they are raised. The placards 25 are preferably of translucent material, such as celluloid, and an incandescent lamp 27 is supported from the bottom of the casing 10 to project light through the placards and make the matter thereon readily visible when the placards are raised. Each of the frames 22 is vertically slidable 80 on the rods 28 which are suitably secured in the cabinet.

Each frame 22 is connected to one of the slides 16 so that, when the slide is withdrawn from the cabinet, the frame will be lifted into raised position, as shown by dotted lines in Figs. 1 and 2, and will be lowered when the slide is pushed back into the cabinet. These connections, between the frames and slides respectively, each comprise a stud 30, projecting from one side of the slide 16, through a slot 31 in guide-bar 15 and extending into a slot 32 in a pivoted arm 33, an arm 34 connected to move rigidly with arm 33, a link 35 pivoted to the outer end of arm 34 and pivoted to a lever 36, which is cross-connected to correspondingly shift a companion arm 37, and vertical links 38 between the ends of arms 36 and 37 and the frame 23. For convenience in pivotally supporting and connecting the arms 33 and 34 of the placard-shifting connections re-

spectively, a shaft 39 is pivotally mounted in bearings 40. One of the arms 33 and one of the arms 34 are fixedly secured to said shaft and the arms on the other connections 5 are cross-connected by sleeves 41 which are mounted one upon the other, as shown in Fig. 5. The cross-connection for the outermost arms 36 and 37 of the placard shifting connections consists of a shaft 42 to 10 which said arms are rigidly secured and which is pivotally held in bearings 43 which are secured in the cabinet. Each cross-connection for the remaining arms consists of a sleeve 44, the sleeves for the connections respectively being mounted one upon the other, as shown in Fig. 6.

A cabinet is provided with a shoe 50 adapted to bear on the floor to frictionally hold the cabinet against lateral movement, 20 the cabinet being usually mounted on casters, so that it may be easily moved from place to place. Shoe 50 is provided with a stem 51 which is slidable in a socket 52 secured to the bottom of the cabinet and is 25 pressed against the floor by a spring 53. The cabinet is usually mounted upon casters 54 and by providing the friction shoe 50, the cabinet will be held against lateral displacement with sufficient force to prevent 30 displacement of the cabinet when the record-holders are operated. A drawer 55 is provided adjacent the bottom of the cabinet for convenience in retaining needles or other parts.

35 When it is desired to place one of the records in the cabinet, the slide 16 for the record-holder, in which the record is held, will be withdrawn from the cabinet. When this is done, the slide will operate through one 40 of its connections, consisting of stud 30, arms 33, 34, link 35, lever-arms 36, 37 and links 38, frame 22, holders 24 and placards 25 carried thereby, to raise the placards into 45 position for exposure through windows 26 and illumination by lamp 27. The upper ends of the holders 24 are open, so that placards 25 may be readily replaced and removed, so that placards which have relation 50 to different records may be placed in the placard holders when the records in the holders 17 are changed. While a given record is being played, the placards containing matter descriptive or illustrative of the record may thus be displayed. For example, for educational purposes, the notes or 55 words of a song may be displayed while the record is being played. After the record has been played, it will be replaced in its holder and, when the holder and record are 60 pushed back into the cabinet, the connections aforesaid will lower the placards when their display will be discontinued.

The invention exemplifies a phonograph cabinet in which the record-holders are 65 operatively connected to exhibiting devices, to

display matter associated with the records when the latter are being reproduced on the phonograph.

The invention is not to be understood as restricted to the details set forth, since these 70 may be modified within the scope of the appended claims, without departing from the spirit and scope of the invention.

Having thus described the invention, what we claim as new and desire to secure by 75 Letters Patent, is:

1. The combination with a phonograph of a series of record disk holders movably mounted in the cabinet and a corresponding series of exhibiting devices connected to 80 the holder and shiftable into operative position thereby.

2. The combination with a phonograph of a series of record disk holders movably mounted in the cabinet, a corresponding 85 series of exhibiting devices connected to the holders and shiftable into operative position thereby, and means for illuminating the devices when they are in operative position.

3. The combination with a phonograph of 90 a series of record-disk holders movably mounted in the cabinet, the latter being provided with display-openings or windows, a series of frames provided with means for holding cards to be exhibited and movable 95 into position for display through the openings, and operative connections between the holders and the frames.

4. The combination with a phonograph-cabinet of a series of record disk holders 100 movably mounted in the cabinet, the latter being provided with display-openings or windows, a series of frames, each provided with a series of card-holders movable into position to display the cards through the 105 openings, and operative connections between the holders and the frames.

5. The combination with a phonograph-cabinet of a series of record disk holders 110 movably mounted in the cabinet, the latter being provided with display-openings or windows, a series of vertically slidable frames provided with card-holders movable 115 into position to display the cards through the openings, and operative connections between the holders and the frames, whereby the frames will be shifted responsively to shift of the disk-holders.

6. The combination with a phonograph cabinet of a series of slides mounted in the 120 cabinet, disk-holders mounted on the slides, exhibiting devices individually connected to the holders respectively and operative connections between the slides and said devices whereby the slides will shift the exhibiting devices into and out of operative position.

7. The combination with a phonograph cabinet of a series of slides mounted in the 125 cabinet, individual disk-holders mounted on the slides, slidable frames carrying card-hold- 130

ers individually connected to the holders respectively, and operative connections between the slides and said devices whereby the slides will shift the card-holders into 5 and out of operative position.

8. The combination with a phonograph cabinet of a series of slides mounted in the cabinet, individual disk-holders mounted on the slides, exhibiting devices individually 10 connected to the holders respectively and operative connections between the slides and said devices whereby the slides will shift the exhibiting devices into and out of operative position, said connections comprising 15 arms and levers between the slides and said devices.

9. The combination with a phonograph cabinet of a series of slides mounted in the cabinet, individual disk-holders mounted on 20 the slides, exhibiting devices individually connected to the holders respectively and op-

erative connections between the slides and said devices whereby the slides will shift the exhibiting devices into and out of operative position, said connections comprising 25 concentrically mounted arms and levers between the slides and said devices.

10. The combination with a phonograph cabinet of a series of slides mounted in the cabinet, individual disk-holders mounted on 30 the slides, exhibiting devices individually connected to the holders respectively and operative connections between the slides and said devices whereby the slides will shift the exhibiting devices into and out of operative position, said connections comprising 35 concentrically mounted arms and concentrically mounted levers between the slides and said devices.

CHARLES S. SPITZER.
JOHN GLOUB.
